KARL HIMMELSBACH, OF ESSEN, GERMANY, ASSIGNOR TO FRIED. KRUPP AKTIEN-GESELLSCHAFT, OF ESSEN-ON-THE-RUHR, GERMANY.

PISTON FOR INTERNAL-COMBUSTION ENGINES.

Application filed August 7, 1925, Serial No. 48,849, and in Germany September 1, 1924.

This invention relates to pistons for internal combustion engines in which the fuel rays ejected by the nozzle strike against the piston head, and it has for its object to favorably influence the process of combustion by a peculiar formation of the surface of the piston head. It is more particularly suited for pistons which have arranged in the piston head an inserted body member adapted to accumulate heat, this being of advantage in the use of certain liquid fuels.

The height of the temperature of the surface of the piston head or of such inserted body member is limited by the resistibility of the material used against heat, by regards to the security of working and by the highest pressure of combustion; on the other hand, this temperature should not fall below a certain minimum amount in order that the necessary quantity of heat may be communicated to all fuel drops within the short space of time at disposal. Now, in order not to pass below a temperature of the piston head recognized as being still effective and to exceed this temperature as little as possible because of the afore-said circumstances to be taken into consideration, the invention has for its object to govern the heating of the fuel drops systematically by a peculiar formation of the active surface of the piston head or inserted body member in such a manner as to cause all fuel particles to absorb heat as uniformly as possible when they strike on the piston head or inserted body member.

According to the invention, this object is essentially attained by making the piston head or inserted body member of such a shape that it presents to the fuel rays striking against it a surface which is as large as possible, and that each fuel drop strikes on a portion of the surface which is as little as possible cooled by preceding fuel drops of the same injection.

An embodiment of the subject-matter of the invention as applied to a piston provided with an inserted body member is illustrated in the accompanying drawing in which

Fig. 1 is a longitudinal section through the piston in a cylinder indicated diagrammatically, and

Figs. 2 and 3 show diagrammatically two other positions of the piston in the cylinder.

The piston body A which is provided in the usual way with piston rings a^1 , carries in a recess of the piston head an inserted body member B, the same being inserted with lateral play so that it may freely expand. The inserted body member B is connected with the piston A by means of a stud-bolt C screwed into the inserted body member B and a nut c^1 . According to the invention, the surface of the inserted body member B lying towards the combustion room is formed in the longitudinal section along a wave-line having a crest of the wave situated on the axis of the piston and between the points at which the fuel strikes the piston. The inserted body member thus shows a central projection b^1 which subsides towards the margin into a trough-like annular depression b^2 . By shaping the inserted body member as described it is attained that the angle which the fuel rays leaving the nozzle at D under a constant angle δ form with the tangent to the wave-line at the point of impact, gradually increases during the process of injection and that a surface as large as possible is presented to the fuel rays and that each fuel drop strikes on a point of the surface little cooled by the preceding fuel drops of the same injection, whereby all fuel particles are caused to absorb the heat uniformly and consequently a good combustion is attained.

In the position of the piston shown in Fig. 1, which corresponds to the beginning of the process of injection, a fuel ray strikes on the inserted body member at the point 1, in the intermediate position according to Fig. 2 it strikes on the member at the point 2 and at the end of the injection when the piston takes the position according to Fig. 3, the fuel ray strikes on the member at the point 3. The point of impact of the fuel ray moves therefore on the distance 1 to 3. This distance is essentially larger than the corresponding distance of the inserted body members of the pistons now in use which have either a flat smooth surface or a shallow depression as indicated in dot-and-dash lines in the drawing. In this last-mentioned form which is still a little more favorable than the inserted body members with a flat surface, the points of impact of the same fuel ray would lie at 1^* , 2^* and 3^* ; a comparison of the distances 1 to 3 and 1^* to 3^* shows that the former dis-

tance is about double as large as the latter. This means that the surface available for the heating of all fuel particles is considerably larger with an inserted body member 5 according to the invention than with the known pistons, and therefore a better effect is obtained.

The invention is more particularly adapted for use in internal combustion engines in 10 which the fuel is injected without the aid of compressed air because, in this case, the fuel rays mostly are more coherent and therefore the local cooling of the inserted body member is greater, but it offers also advantages in engines where the injection is effected by means of compressed air.

Claim:

In an internal combustion engine, a cylinder, a piston in said cylinder, and means for injecting non-vaporized fuel into said cylinder toward said piston in obliquely directed streams, the surface of the piston toward the fuel injector being of such shape that in any diametrical longitudinal section of the piston it appears as a wave line curving downwardly 20 and outwardly from the points at which the fuel strikes the piston in its upper dead center position and then curving upwardly.

The foregoing specification signed at Cologne, Germany, this 15th day of July, 1925.

KARL HIMMELSBACH.
